UNITED STATES PATENT OFFICE.

JOHN A. FRAZIER, OF LILLY CHAPEL, OHIO.

CAR-COUPING.

SPECIFICATION forming part of Letters Patent No. 267,868, dated November 21, 1882.

Application filed June 24, 1882. (No model.)

To all whom it may concern:

Be it known that I, JOHN A. FRAZIER, a citizen of the United States, resident at Lilly Chapel, in the county of Madison and State of Ohio, have invented a new and valuable Improvement in Car-Couplings; and I do hereby declare that the following is a full, clear, and exact description of the construction and operation of the same, reference being had to the annexed drawings, making a part of this specification, and to the letters and figures of reference marked thereon.

Figure 1 of the drawings is a plan view of my car-coupler. Fig. 2 is a side view of the same. Fig. 3 is a vertical longitudinal section view. Fig. 4 is a plan view of the link, and Fig. 5 is a vertical section of the link.

This invention has relation to devices for coupling cars automatically; and it consists in the construction and novel arrangement of the draw-heads, recessed longitudinally from above downward and provided with a spring-bearing in a raised rear portion of the recess; the hooked coupling-caps for said draw-heads, having stop-shoulders to receive the links in rear of their hooked ends, said caps being let into the recessed draw-heads and pivoted thereto in front of the spring-bearings; the transverse bearing and brace for the front portion of the coupling-cap, as will be hereinafter fully described and claimed.

In the accompanying drawings, the letter A designates the draw-heads, each of which is longitudinally recessed from the rear abutment or wall, b, forward, the recess opening clear at the front end or mouth of the draw-head. The bottom c of the recess is somewhat raised in rear, as at d, and in this raised portion is formed a recessed seat, e, for the reception of a strong spiral spring, F.

G indicates a cap-plate or coupling-cap, which forms the top of the draw-head between the side walls, H, thereof, said cap being let in between said side walls, so as to be flush with their upper edges. A transverse pivot-bolt, k, arranged a short distance in front of the spring F, serves to connect the cap-plate to the bearings l in the side walls, H, of the draw-head. The front part of the cap G is formed with a coupling-hook on its under side,

having a convex rounded bearing, as indicated at m, and in rear of this hook is formed, also on the under side of the cap, an abutment-shoulder, n, of sufficient depth to engage the nose or beveled end of the coupling-hook P when the latter is inserted in the mouth of the draw-head.

In the forward portion of the draw-head, under the cap, and engaging the shoulder n thereof in the angle thereof, is a bearing and draft-brace, R, which may be in the form of a transverse bolt, as shown in the drawings. This brace-bearing serves to form a rest for the coupling-cap, and also to take the strain of the draft in great measure off the pivot-bolt k by its engagement with the shoulder n of said cap.

Through the top and bottom of each draw-head are usually provided the perforations s, for the reception of a coupling-pin to be used with the ordinary loop-link in coupling with cars provided only therewith; or the coupling-hook P, which is formed with the upwardly-turned hooks z on its ends, may be made with slots t to receive vertical coupling-pins. The coupling-hook P is formed without lateral wings or projections, and is designed to engage the hook ends m of the coupling-caps G, and its hooks z are made with rounded convex bearings, to swing easily from side to side when engaged with the cap-hooks. Flexure of the coupling devices is thus provided for. The width of the hooked coupling-bar P is designed to be as great as its depth at the hooked end and greater than its depth in the shank, so that if a car should jump the track and turn as much as the quarter of a circle an uncoupling will automatically result.

A lever, v, can readily be connected to the top of the cap, as indicated in the drawings, and pivoted to a bearing, w, of the frame of the car, so as to extend laterally outward and form a handle, whereby the hook end of the cap-plate can be raised to enable the coupling-hook to be withdrawn; and to the lever v or directly to the cap-plate an operating-rod, j, may be extended upward in bearings to the platform or top of the car to enable the cap-plate to be operated therefrom.

A recessed draw-head provided with a spring-

actuated hooked lever and a pivoted hook, the lever lying wholly within the draw-head and the hook extended beyond the draw-head and adapted to enter an opposite draw-head and engage the lever-hook thereof, has been used prior to my invention. An abutment for preventing the coupling-bar from entering too far is also old in this class of couplings; and I claim neither construction, broadly, herein.

10 Having described this invention, what I claim, and desire to secure by Letters Patent, is—

15 In a car-coupling, the draw-head A, recessed longitudinally from the rear wall or abutment, b, forward, and having a spring-bearing, e, and

spring F in its rear portion, the hooked coupling-cap G, let in between the side walls of the draw-head and pivoted thereto, the stop-shoulder n of said cap in rear of its hook, and the transverse bearing and brace R for the front 20 part of the coupling-cap, substantially as specified.

In testimony that I claim the above I have hereunto subscribed my name in the presence of two witnesses.

JOHN A. FRAZIER.

Witnesses:

JOHN M. SHAFFER,
PIERCE GEORGE.
